PORTABLE ASH TRAY

Price D. Rice, Mount Clemens, Mich.

Application May 19, 1953, Serial No. 356,023

2 Claims. (Cl. 131—242)

1

This invention relates to ash trays, and more particularly to an improved portable ash tray of a type suitable to be carried around by the user and which is readily available for use whenever required.

A main object of the invention is to provide a novel and improved portable receptacle for cigarette ashes and the like, said receptacle being simple in construction, being easy to manipulate, and being collapsible to a compact size so that it may be readily carried in the user's pocket.

A further object of the invention is to provide an improved portable receptacle for cigarette ashes and the like, said receptacle being inexpensive to manufacture, being sturdy in construction, being easy to expand and contract, as required, being provided with easily operated closure means which may be moved to a securely closed position so that the contents of the receptacle will not spill, being light in weight and being attractive in appearance.

Further objects and advantages of the invention will become apparent from the following description and claims, and from the accompanying drawings, wherein:

Figure 1 is a top plan view of an improved portable receptacle constructed in accordance with the present invention.

Figure 2 is a side elevational view of the receptacle of Figure 1, shown in a collapsed position.

Figure 3 is a side elevational view of the receptacle of Figure 1 shown in an expanded position.

Figure 4 is another elevational view of the receptacle, shown in the position of Figure 2, said view being taken at right angles to the direction of the view shown in Figure 2.

Figure 5 is an enlarged vertical cross sectional view taken on the line 5—5 of Figure 1.

Figure 6 is an enlarged cross sectional detail view taken on the line 6—6 of Figure 5.

Figure 7 is a perspective view of the receptacle of Figures 1 to 6, shown in expanded position.

Referring to the drawings, 11 generally designates the receptacle, said receptacle comprising a generally cylindrical outer housing portion 12 which is telescopically engaged with a lower inner housing portion 13, said inner housing portion 13 having the bottom wall 14, and the housing portions 12 and 13 being generally cylindrical in shape. As shown in Figure 5, the lower housing portion 13 is provided with two pairs of diametrically opposed vertical grooves 15 spaced at angles of 90° around its circumference, as illustrated, each of the vertical grooves 15 terminating at its top end in a horizontal groove portion

2

16. Received in the grooves 15 are inwardly projecting lug elements 17 carried by the inside bottom marginal surfaces of the outer housing section 12, the lugs 17 being slidable in the grooves 15, and being arranged so that the outer housing 12 may assume an extended position relative to the inner housing 14 by rotating said housing through a small angle relative to the inner housing 14, whereby the lug elements 17 will be received in the horizontal groove portions 16, thus placing the receptacle in its expanded position shown in Figures 3, 5, and 7. The receptacle may be collapsed to the position shown in Figures 2 and 4 by reversing the rotation of the outer housing member 12 relative to the inner housing member 14 to align the lug elements 17 with the vertical grooves 15, and then merely compressing the two housing portions to cause the inner housing portion 13 to be telescoped inside the outer housing portion 12.

Hingedly connected to the rim of the upper housing portion 12 at 18 is a generally circular cover member 19, the hinged connection 18 being provided with the biasing springs 20 acting between the inner wall surface of housing section 12 and the cover 19 to bias the cover upwardly to the dotted view position thereof shown in Figure 4. The cover 19 is provided with a peripheral depending flange 21, and mounted slidably in diametrically opposing relationship in the flange 21 are the locking members 22, each locking member comprising a shank portion 23 which is slidably received in an aperture in the flange 21, the shank portion 23 having integrally connected thereto at its inner end a hook 24 and being integrally formed at its outer end with the button element 25. Engaged between the button element 25 and the external surface of the flange 21 beneath the shank portion 23 of each locking member is a coiled spring 26 which biases the locking member outwardly and thus exerts a biasing force on the hook 24 of each locking member. The inner surface of the housing section 12 is formed with detent recesses in which the pointed ends of the hook elements 24 are lockingly engageable, as illustrated in Figure 5, whereby the cover 19 may be locked in closed position. To release the cover, it is merely necessary to press the opposed button elements 25, inwardly, whereby the hook elements 24 of the associated locking members 22 disengage from their seats in the wall of the housing section 12, allowing the cover 19 to open to the dotted view position thereof shown in Figure 4 by the biasing action exerted on said cover member by coiled springs 20.

As shown in Figure 5, the pointed ends of the hook elements 24 are preferably beveled in the manner illustrated, whereby the hook elements will slip into locking engagement in the recesses provided therefor in the inner wall surface of housing member 12 when the cover is manually moved to its closed position.

As shown in Figure 5, the locking elements 22 are preferably located on a diameter parallel to the hinge 18 and spaced angularly 90° from the location of said hinge on the rim of the outer housing section 12.

The top cover 19 is formed with pairs of aligned, radially extending grooves 27, 28 and 29, 30 and with a central, substantially circular opening 30' communicating with the said grooves. As shown in Fig. 1, the grooves 27, 28 are preferably narrower than the grooves 29, 30, and the central opening 30' is slightly larger in diameter than the width of the larger grooves 29, 30. Slidably carried in the cover and the grooves 27, 28 for radial sliding movement toward and away from the central opening 30' are the channeled, upwardly concave rest members 31, 32, and slidably carried in the grooves 29, 30 are the upwardly concave channeled rest members 33, 34, the rest member 33 being integrally formed at its inner end with a circular, upwardly concave cover element 35 which is adapted to overlie the central aperture 30' of the top cover when the rest member 33 is in the normal position thereof shown in Figure 7. The rest members 31, 32, 33 and 34 may be made of thin sheet metal or the like, and the edges of said rest members may be slidably received in guide grooves 36 formed in the side walls of the grooves 27 to 30. Each rest member is formed adjacent its outer end with a transversely extending slot 37 in which a fingernail may be engaged so that the user may slide the associated rest member outwardly, if so desired, as where it is desired to employ the rest member for supporting a cigarette or the like thereon.

The narrower rest members 31 and 32 may be employed for supporting cigarettes, whereas the wider rest members 33 and 34 may be used for supporting cigars.

Normally, the receptacle is carried in the user's pocket and is in its collapsed position, shown in Figure 2. When it is desired to use the device as an ash tray, the user extracts the receptacle from his pocket and expands the receptacle to the position shown in Figures 3, 5 and 7 and the receptacle may be placed in its expanded position, as above described, by engaging the lug elements 17 in the horizontal groove portions 16. The cigarette ashes and the like may be emptied into the receptacle by sliding the rest member 33 outwardly, providing access to the interior of the receptacle through opening 30'. The receptacle may be closed by returning the rest member 33 to the position shown in Figure 7, after which

the receptacle may be collapsed to the position shown in Figures 2 and 4 and may be returned to the user's pocket.

When it is desired to empty the receptacle, the top cover 19 is opened by pressing the button elements 25 inwardly, releasing the cover and allowing the springs 20 to open the cover to the dotted view position shown in Figure 4. After emptying, the cover may be closed and the receptacle may be placed in the user's pocket until needed for further use.

While a specific embodiment of an improved portable receptacle for cigarette ashes and the like has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A portable receptacle for cigarette ashes and the like comprising a housing having a removable top cover, means releasably securing said cover on said housing, said top cover being formed with a central opening, a plurality of channeled upwardly concave rest members slidably mounted in said top cover and extending from the edge thereof to said opening, and a cover plate carried by one of said rest members and being arranged to normally overlie said central opening, said opening being exposed when said one of the rest members is moved away from the central portion of the cover.

2. A portable receptacle for cigarette ashes and the like comprising a housing, said housing comprising a plurality of slidably connected telescoping sections, whereby said housing is adjustable in size, a top cover hingedly connected to the rim of the uppermost housing section, means releasably securing said top cover in closed position on said uppermost section, said top cover being formed with a central opening, a plurality of channeled, upwardly concave rest members slidably mounted in said top cover and extending from the edge thereof to said opening, and a cover plate carried by one of said rest members and being arranged to normally overlie said central opening, said opening being exposed when said one of the rest members is moved away from the central portion of the cover.
